FIG. 1.

FIG. 2.

FIG. 4.

FIG. 5.

FIG. 3.

INVENTOR
CHARLES F. ECKLER

BY *Charles F. Eckler*
ATTORNEY

UNITED STATES PATENT OFFICE.

CHARLES F. ECKLER, OF INDIANAPOLIS, INDIANA.

STEP PLATE.

Application filed July 1, 1922. Serial No. 572,243.

To all whom it may concern:

Be it known that I, CHARLES F. ECKLER, a citizen of the United States, residing at Indianapolis, in the county of Marion and 5 State of Indiana, have invented certain new and useful Improvements in Step Plates, of which the following is a specification.

This invention relates to improvements in step plates and is designed primarily for 10 use in connection with automobiles and similar vehicles, the prime feature of the invention being the provision of a plate or frame adapted to be secured over a rubber or other form of pad and then connected in any suitable manner to the running board of the 15 vehicle for holding the pad in position.

A further feature of the invention is the provision, in connection with the frame, of means for cleaning the soles of the shoes of 20 excess mud or the like before applying the shoes to the cleaning pad.

A further feature of the invention is the provision, in connection with the sole cleaning mechanism, of means for removing dirt 25 or the like from the edges of the soles of the shoes.

And a further feature of the invention is the provision of a toe plate or shield for protecting the sides of the vehicle adjacent 30 to the step plate.

Other objects and advantages will be hereinafter more fully set forth and pointed out in the accompanying specification.

In the accompanying drawings, 35 Figure 1 is a detail perspective view of the running board of an automobile showing a step plate thereon,

Figure 2 is a top plan view of the step plate,

Figure 3 is a front elevation thereof,

Figure 4 is a sectional view as seen on line 40 4—4, Figure 2, and

Figure 5 is a detail perspective view of the shoe cleaning portion of the step plate.

Referring to the drawings, 1 indicates the 45 running board of an automobile or similar vehicle which may be of any preferred construction, and 2 indicates a part of the side wall of the vehicle.

In order to properly remove soil or other 50 foreign particles from the soles of the shoe before entering the vehicle, a step plate is attached to the running board comprising a pad 3, preferably of rubber or similar material, having its upper face ribbed so that by drawing the foot across the pad the soles

of the shoes will be properly cleaned of any foreign particles. Surrounding the edges of the pad 3 is a frame 4, preferably of metal, the edges of the pad 3 having extensions 5 which project under and fit in recesses 6 in the under face of the frame 4, the thickness of the extensions being such that when the frame 4 is properly secured to the running board 1, the pad will be securely locked 65 within the frame.

To prevent the toe of the shoe striking against the side face of the vehicle body, a toe plate or shield 7 is extended upwardly from the inner edge of the frame 4 so that 70 the toe of the shoe, when being moved over the face of the pad 3, will strike said shield and not come in contact with any part of the vehicle, this also being true when entering or leaving the vehicle. Formed on the 75 outer edge of the frame 4 is a scraper plate 8 which is preferably formed integral with the frame and is spaced from the edge of the frame so that when the shoe is drawn over the scraper the soil removed therefrom 80 will readily pass between the scraper and the edge of the frame, the scraper being preferably provided with a reinforcing rib 9 at its longitudinal center.

In the event of an accumulation of soil 85 at the edges of the soles of the shoe or upon the heel of the shoe notches 10 are formed in the upper edge of the scraper plate 8, preferably on opposite sides of the rib 9, said notches being preferably inclined and 90 so constructed that they will provide vertical shoulders 11, which when the shoe is entered in one of the notches and moved inwardly or outwardly will scrape the edges of the sole or heel of the shoe and remove 95 any soil which may be adhering thereto.

The step plate is secured to the running board in any suitable manner, as by means of screws 12, which are preferably countersunk so as not to project above the face of 100 the frame, through which they extend, and as the scraper plate 8 has its upper edge terminating substantially flush with the upper face of the frame 4 there will be no projections to interfere with the placing of 105 the foot upon the step plate and there will be no parts projecting so as to catch on the garments of the occupant of the vehicle when entering or alighting from the same.

By constructing the step plate in the manner shown, the frame and parts associated therewith, may be constructed of aluminum 110

or similar light material without detracting from its strength and durability, and by constructing the pad and frame in the manner shown the pad will be securely held in position on the running board when the frame is properly secured thereover.

Having thus fully described my said invention, what I claim as new and desire to secure by Letters Patent, is:

10 In a step plate, a frame, a scraper plate at one edge of said frame and spaced therefrom to provide an opening, said scraper plate having notches in the upper edge thereof forming vertical shoulders for engage-

ment with the edges of the soles of shoes 15 when moved over the scraper plate, the top edge of said plate and the top end of said shoulders terminating flush with the top face of said frame.

In witness whereof, I have hereunto set 20 my hand and seal at Indianapolis, Indiana, this 16th day of June, A. D. nineteen hundred and twenty-two.

CHARLES F. ECKLER. [L. S.]

Witnesses:

CAREY S. FRYE,
M. L. SHULER.
